panyApplication July 29, 1935, Serial No. 33,626
In Great Britain June 6, 1935

5 Claims. (Cl. 33—22)

This invention relates to means for producing or marking out designs upon very heavy rollers for colour printing purposes, making use of pantograph or similar apparatus for reproducing to 5 a reduced scale on the waxed or varnished or treated roller the design by working the tracing point of the tracing arm over the design to be traced out or transferred onto the roller. Pantograph tracing or transferring apparatus is, of course, well known.

In the ordinary pantograph engraving machine the movement of the tracing arm by the operator in a longitudinal direction moves the point of the tracing lever in a lateral direction, whilst the 15 movement of the tracing arm laterally on either hand causes the roller or object to be engraved to be rotated, all whereby any design can be engraved on or transferred to the roller or object.

This is satisfactory when the object to be engraved (say a roller) is of reasonable weight, but cannot be applied for the engraving of heavy bowls or rollers which may weigh up to five tons. As a consequence, such very heavy rollers have been engraved by hand, which is a long and 25 expensive process.

In order to be able to mechanically trace the design to be produced on very heavy rollers, we make use of an arrangement wherein the whole of the movement necessary for any one tracing 30 operation on the roller is conveyed to the tracing levers, the heavy roller itself remaining stationary during such operation and being independently mounted and having means for rotating the roller by hand as required. Such an arrangement 35 is broadly known, but according to our improvements we propose to carry the tracing levers in connection with a compound slide structure which includes superposed rolling bars, such compound slide structure being located above the heavy 40 roller to receive the design. One set of rolling bars (upon which the tracing levers may be supported) conveys the lateral motion and the other set conveys the longitudinal motion, the combination providing a compound slide structure from 45 which any necessary motion can be conveyed from the design by the tracing arm through the superposed rolling bars to the tracing levers.

The tracing levers are so supported from the rolling bars as to be adjustable longitudinally 50 with respect thereto to operate upon any desired portion axially of the heavy roller, and a plurality of such tracing levers can be arranged to trace the design on a number of sections axially of the roller with one tracing operation. Also, co-oper- 55 ating means are provided for raising and lower-

ing the tracing levers with respect to the heavy roller.

We mount the heavy roller in supports located in a free space below the superposed rolling bars of the compound slide arrangement and this roller is adapted to be turned by hand through simple mechanism, there being suitable indexing mechanism to govern the turning of the bowl as and when required, that is when one section of the tracing or engraving has been effected. 10

The improvements are illustrated in the accompanying drawings, wherein:—

Fig. 1 is a plan view of the upper part of the machine including the pantograph mechanism and the upper rolling bars, and shows the swivel 15 bracket pivoted over one rolling bar, and also the fulcrum for the rhomboid.

Fig. 2 shows a broken end view of the machine with certain of the parts in section. The continuation of the foot treadle is shown at Fig. 2a 20 for want of room on the sheet.

Fig. 3, which is shown on two sheets of drawings, is a rear view of the machine and indicates the heavy roller in position and shows the mechanism for dealing with such heavy roller whilst 25 the design is being traced or transferred.

Fig. 4 is a detail of means to couple the upper rolling bars.

Fig. 5 is a separate enlarged detail showing how 30 the tracing levers are mounted and controlled from treadle mechanism, such Fig. 5 showing the tracing levers lowered onto the heavy roller.

Fig. 6 is a view similar to Fig. 5, but with the tracing levers raised.

Fig. 7 shows a rear view of certain of the parts 35 seen in Fig. 5.

Referring in the first place and more particularly to Fig. 1, there is shown the work-table *a* upon which the design to be traced is secured, and over such table is the tracer arm *b*¹ of a 40 rhomboid pantograph mechanism *b* with joints at *b*², the fulcrum of the pantograph structure *b* being at *b*³. The disposition of the rhomboid pantograph laterally or longitudinally of the table is provided for by adjustment brackets *b*⁴, *b*⁵. 45

Such a rhomboid pantograph mechanism is broadly known as to its action. It is shown as receiving support from a castor *b*⁶ which rolls over a surface plate *c* supported by brackets *c*¹, *c*². The arm on the left (Fig. 1) of the rhomboid 50 pantograph mechanism is adjustably bolted to a swivel bracket *b*⁷ which works about a pivot *d* fixed on an adjustable slide *d*¹ mounted on a plate *d*² with undercut sides screwed to one of the top rolling bars *e*, *e*. The top rolling bars *e*, *e* 55

may be interconnected by brackets e^1, e^2 with adjusting screws e^3 so as to move together (as shown by Fig. 4) or they may be connected by flexible bands e^4 passing around a roller e^5 so as to effect 5 a reverse movement when producing parts of design of opposite hands, this being well known.

The machine comprises a bed casting f to which castings f^1, f^1 are bolted, upon which are bolted bridge or extension castings f^2 having their fore- 10 ends interconnected by a cross-arm casting f^3 and having attached pendent brackets f^4 . Stout cross-bearers g, g with guide rail g^1 extend between the castings f^1, f^1 and the pendent brackets f^4, f^4 , as well shown in Fig. 2, and these cross-bearers g, g support the rolling elements. The 15 properly shaped top rolling bars e, e roll on anti-friction rollers e^6 which in turn roll on shaped rails e^7 secured to shaped bars e^8 which roll on anti-friction rollers g^2 which engage the stout 20 cross-bearers g, g .

Depending from the ends of the rolling bars e, e are brackets h^1 and in spaced relationship longitudinally there are stirrup-like brackets h^2 , which brackets h^1 and h^2 support movable lower 25 bars h with bevelled sides.

According to the foregoing, if the tracer arm b^1 be moved laterally it will move the rolling bars e, e laterally upon the anti-friction rollers e^6 , and if the tracer arm b^1 be pushed in the direction 30 of its length it will cause the rolling bars e^8, e^8 and what they support to roll on the anti-friction rollers g^2 and so move in a direction at right-angles to a lateral actuation. Thus, both 35 motions from the rhomboid or pantograph structure are conveyed through the compound slide provision described so that any motion which is derived therefrom or which is a compound of a lateral and longitudinal motion is obtainable and can be conveyed to the tracing lever or levers 40 to act on the heavy roller to which the design in reduced form is to be transferred.

The tracing levers i are adjustably mounted in brackets i^1 which are spaced upon the lower bars h suspended from the rolling bars e, e and two 45 sets are indicated by the drawings and in particular by Fig. 2.

The compound slide mechanism is clearly shown as suspended or superposed from carrying framework located over support provision for the heavy 50 roller r which is to receive the design traced by the diamond points of the tracer levers i, i .

In order to raise and lower the tracer levers to lift same out of, or to lower same into action, the tracing levers i are shown pivoted each upon 55 a bracket i^1 adjustable along the lower bars h by clamping devices i^2 .

The tracing levers i are shown fulcrumed at i^3 in the brackets i^1 and counterbalanced by a weight i^4 and are controlled each by a cam j 60 bearing on an adjustable stud j^5 . The cams j are mounted on a shaft j^1 mounted in end bearings j^2 and spaced intermediate bearings j^3 , the cams j being gripped on the shaft j^1 . Lever arms k are gripped on the shaft j^1 and are loaded by an 65 adjustable weight k^1 . Upon the shaft j^1 are fixed spaced arms j^4 each set supporting a bar j^5 . Over the bars j^5 at each end of the machine is located a parallel bar l with contact plates l^1 which bear 70 on the bars j^5 and depress or relieve same. Said parallel bars l are suspended as to one end on a link or lever l^2 and as to the other end are pivoted to a bell-crank lever l^3 fulcrumed at l^4 . Adjustable connecting rods l^5 connect the bell-crank 75 lever l^3 to a treadle l^6 . This treadle l^6 is fulcrumed at l^6 to adjustable brackets l^7 supported

in slides on the bed casting f , the adjustable brackets l^7 permitting the position of the treadle with respect to the working platform to be regulated to suit the comfort of the worker. Weights l^8 are applied to the treadle levers l^9 . When the 5 treadle is pressed down (which occurs when the worker is operating) the bell-crank levers l^3 are moved so as to act on the parallel bars l and raise same, thus allowing the tracer levers i to be lowered onto the roller r (see Figs. 2 and 5). If the 10 foot be taken off the treadle then the weights l^8 acting through the connecting rods l^5 lower the parallel bars l which acting on the bars j^5 move the cams j and raise the tracer levers i off the roller (see Fig. 6).

As to the heavy roller, this is arranged to be supported below the over-head compound slide arrangement worked by the pantograph mechanism to impart the two motions to the tracing levers. There are shown two supporting structures which are like "jacks". They each comprise a base m and screw device m^1 with worm wheel m^2 and nut, the worm wheel being operated by a worm m^3 worked through a shaft m^4 . Upon each screw device m^1 is mounted a bed plate m^5 . This bed plate m^5 carries on its upper surface a slide n with provision such as anti-friction rollers n^1, n^1 to support the mandrel r^1 of the heavy roller r . Said slides n are adjustable each by means of a nut and screw n^2 , the 30 screw n^2 being operated through a worm-wheel n^3 actuated by a worm n^4 on the shaft n^5 to which a handle can be applied. By such arrangements we provide for the raising, lowering and adjustment or setting of heavy rollers of varying diameter (in the space available below the rolling bar structures supported overhead) with respect to the tracing levers. Also for setting the heavy roller backwards or forwards to the tracing 35 levers.

Upon the mandrel r^1 of the heavy roller r is mounted the indexing wheel o the same being shown fixed by a cone grip o^1 , the indexing wheel having spaced holes in its periphery as shown, and the shown locking pin o^2 is provided to release for adjusting and to hold the indexing wheel o when adjusted. In order to turn the heavy roller r to present a new area to the tracing levers, a cone grip p is shown fixed on the mandrel r^1 , and with this cone grip p a worm 50 wheel p^1 is combined adapted to be turned by a worm p^2 mounted on the shaft p^3 . The operation of the indexing wheel is done as and when required, that is when the sets of tracing levers have done their work over the required areas 55 as is understood.

It will be appreciated that there is imparted to the tracing levers both lateral and longitudinal motion (which is required) entirely through the compound slide arrangement from the over-head pantograph mechanism which obviates having to move the heavy roller at all through or from the pantograph mechanism, the mounting and movement of the roller being independent and manually performed (as and when required) 60 through mechanism standing on the floor. Thus the pantograph mechanism is relieved from a service that it normally performs, but which it can not perform in the case of very heavy rollers. Further we arrange in practical manner for the ready getting into position and removal and independent adjustment of the heavy rollers as and when required.

If no reduction in the transferred design be desired, the rhomboid structure could be dis- 75

pensed with, and a hand controlled directing lever or bracket could be pivotally attached to one of the upper rolling bars of the compound slide structure.

5 We declare that what we claim is:

1. Apparatus for producing designs on very heavy rollers comprising a framework, a compound slide structure including superposed rolling bars located above the heavy roller, means to actuate said rolling bars, tracing levers supported from said rolling bars and adjustable longitudinally with respect thereto to operate upon any desired portion axially of the heavy roller, said superposed rolling bars being arranged to move the tracing levers during each tracing operation in a lateral and a longitudinal direction and in any direction which is a combination of the two whilst the heavy roller is held stationary.

20 2. Apparatus for producing designs on very heavy rollers comprising a framework, a compound slide structure including superposed rolling bars located above the heavy roller, pantograph mechanism operatively connected to said rolling bars, tracing levers supported from said rolling bars and adjustable longitudinally with respect thereto, and means to raise and lower said tracing levers with respect to the heavy roller, said superposed rolling bars being arranged to move the tracing levers during each tracing operation in a lateral and longitudinal direction and in any direction which is a combination of the two whilst the heavy roller is held stationary.

25 3. Apparatus for producing designs on very heavy rollers comprising a framework, bracket structures mounted thereon, a compound slide structure including superposed rolling bars supported by said bracket structures above the heavy roller, tracing levers supported from said rolling bars and adjustable longitudinally with respect thereto, pantograph mechanism operatively connected to said rolling bars and arranged to convey motion in a horizontal plane from the tracer

arm to said tracing levers during each tracing operation whilst the heavy roller is held stationary, and means to raise said tracing levers clear of the heavy roller automatically and to lower them manually for tracing.

4. Apparatus for producing designs on very heavy rollers comprising a framework carrying brackets, a compound slide structure including superposed rolling bars and anti-friction rollers supported by said brackets above the heavy roller, tracing levers pivoted in brackets supported from said rolling bars and adjustable longitudinally with respect thereto, pantograph mechanism operatively connected to one of said rolling bars and arranged to actuate said tracing levers through the rolling bars in a horizontal plane, whilst the heavy roller is held stationary, and means operated by parallel bars and treadle mechanism to raise said tracing levers clear of the heavy roller automatically and to lower them manually for tracing.

5. Apparatus for producing designs on very heavy rollers comprising a framework carrying depending brackets, a compound slide structure including superposed rolling bars and anti-friction rollers supported by said brackets above the heavy roller, lower bars carried from the upper set of rolling bars, tracing levers pivoted in brackets supported on said lower bars and adjustable longitudinally with respect thereto, rhomboid pantograph mechanism adjustably connected to one of said upper set of rolling bars and arranged to actuate said tracing levers through the rolling bars in a horizontal plane, whilst the heavy roller is held stationary an adjustable fulcrum for said pantograph mechanism, and cam mechanism operated by parallel bars and treadle mechanism to raise said tracing levers clear of the heavy roller automatically and to lower them manually for tracing.

40
GEORGE PERCIVAL VARLEY.
ADAM CLARKE.
